UNITED STATES PATENT OFFICE

MARCIA CAHN BOHR, OF SAN FRANCISCO, CALIFORNIA

COMBINATION TROUSER SKIRT

Application filed April 29, 1930. Serial No. 448,310.

My invention relates to improvements in combination trouser skirts, and it consists in the combinations, constructions and arrangements hereinafter described and claimed.

5 An object of my invention is to provide a combination trouser skirt that is designed to be worn by female adults and children.

The trouser skirt employs an inverted pleat slightly lapped or just meeting at the 10 stitching, which covers the crotch and completely hides the trouser appearance. This inverted pleat is used in conjunction with any other pleats, such as side pleats, box pleats, knife pleats or accordion pleats, or any type 15 of pleats being used, either all around, part way around, clusters, groups, etc.

Other objects and advantages will appear as the specification proceeds, and the novel features of the device will be particularly 20 pointed out in the claims hereto annexed.

My invention is illustrated in the accompanying drawings, in which

Figure 1 shows a perspective view of the device as applied to a dress,

25 Figure 2 shows a side elevation,

Figure 3 shows a rear elevation,

Figure 4 shows an enlarged front view of the skirt with the trouser portions flared outwardly,

30 Figure 5 shows the device in normal position, and

Figure 6 is a detail cross section taken on the line 6—6 of Figure 4.

In carrying out my invention, I provide a 35 skirt portion 1 shown in Figure 4. This skirt has a crotch 2 that divides the skirt into two leg portions 3 and 4.

The crotch, the most important part of my invention, is so designed in length to give 40 freedom of movement in all bending postures, as in athletics, various sports, as golf, swimming, tennis, motoring, such as entering in or out of a car, horseback riding, and so forth.

The trouser seam 2' is cut on a slight arc 45 although it could be on a slant from the end of the crotch to the bottom of the skirt to eliminate unnecessary material which interferes in wearing. The trouser skirt is joined to a yoke 7 or it may form a continuation of 50 a dress, swimming suit, etc. The yoke 7

forms a tight fit around the body and prevents the skirt from sagging in front and back. This causes the pleats disposed adjacent to the crotch to hang vertically and cover the crotch.

55 The crotch is normally covered or concealed by pleats 5 that are integral with the crotch and the skirt. The pleats disposed adjacent to the crotch are inverted, but the other adjoining pleats may be made otherwise if desired, or dispensed with. An inverted pleat is a reversed box pleat and in the garment as shown the box pleat is formed into a crotch portion and then into portions that form the inner sides of the legs of the garment. The pleats forming the inverted pleats at the top of the garment extend downwardly throughout the length of the garment and abut each other for hiding the crotch. The inverted pleat is shown in Figure 6, which 60 especially illustrates the slight lapping at 5' and the meeting of the edges at the central stitching 8. The pleats are stitched together at their tops at 8, and these stitchings prevent the opening of the pleats adjacent to the top of the crotch in the region 9 (front and back), and therefore the crotch will be effectively covered at all times. The length of the stitchings 8 may vary according to how 65 much of the crotch it is desired to cover. In Figure 6 I show how the pleats 5 disposed adjacent to the crotch slightly overlap as at 5', and how they are secured together by the stitching 8. This causes the central pleats to 70 hide the crotch during walking.

This trouser skirt is not only adapted for street and formal wear but is adapted for pajamas, swimming suits, school and gymnasium dresses for children, and party dresses, etc. The inverted pleats (Fig. 4) 75 have the connecting and joined web portions 10 of such extent as to form the crotch or, in other words, the inner leg portions.

Although I have shown and described one 80 embodiment of my invention, it is to be understood that the same is susceptible of various changes, and I reserve the right to employ such changes as may come within the 85 scope of the claims hereto annexed.

I claim:

1. A combination trouser skirt having a crotch formed therein for providing leg portions, inverted pleats disposed adjacent to the crotch for hiding the crotch, said pleats being overlapped at their tops for causing their lower portions to abut during walking and thus cover the crotch at all times, and a row of stitching connecting the pleats and holding the tops of said pleats in place.
2. A skirt of the character described comprising two side sections folded at their edges to form pleats throughout the lengths thereof, meeting in the front and in the back, the pleats of the two sections being overlapped and secured at the upper portion of the skirt only to normally cause the lower sections of the pleats to lie in circumferential continuity, and a web connecting the front and the back pleats of each section to form the crotch and to form separate leg sections.
3. A skirt comprising two side sections folded at their edges to form pleats throughout the lengths thereof, meeting in the front and in the back, the pleats of the two sections being overlapped and secured at the upper portion of the skirt only to normally cause the lower sections of the pleats to lie in circumferential continuity, a web connecting the front and back pleats of each section to form the crotch and to form separate leg sections, and other pleats in said side sections adjoining the first pleats also being secured at the upper portion of the skirt only.
4. A skirt of the character described having an inverted pleat in the front and an inverted pleat in the back, both of said pleats extending to the bottom of the skirt, the webs of the two pleats being joined between the legs to form a crotch and the webs having sufficient material to normally allow the folds to preserve the character of circumferential continuity throughout the skirt length.
